UNITED STATES PATENT OFFICE.

MARTIN L. NELSON, OF PARK RIDGE, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MULTIOFFICE TELEPHONE SYSTEM.

Application filed January 18, 1924, Serial No. 386,946. Renewed August 29, 1927.

The present invention relates to multi-office telephone systems in general, but is concerned more particularly with mixed systems in which certain of the offices are 5 manual offices and in which certain of the offices are automatic offices; and the invention is principally concerned with the handling of calls originating in a manual office and intended for a subscriber whose line 10 terminates in an automatic office.

This case may be considered an improvement on my prior case, Serial No. 443,688, filed February 9, 1921, and when considered in the light of this prior case, the principal 15 feature of the present invention relates to the provision of new and improved circuit arrangements whereby the "B" operator's senders are common to a plurality of "B" operators instead of being individual to one 20 operator.

A further feature of the present invention relates to the provision of new and improved circuit arrangements whereby only one set of controlling push buttons is required at a "B" operator's position for the 25 purpose of setting up the desired numbers, arrangements being provided for associating the common push buttons with a new sender while the sender last used is still sending out 30 the number indicated by the associated register.

It is specifically an object of the invention to provide a step by step switch individual to the above mentioned set of push 35 buttons which disassociates the push buttons from the register sender last used and automatically associates the push buttons with a new sender independent of any special act on the part of the operator.

A further object of the present invention 40 is to simplify the circuits through which the push buttons control a selected register sender so as to permit a relatively small number of wipers to be used on the switches 45 which complete the connections from the push buttons to the register senders.

There are several other objects of the present invention which may be classified broadly as having to do with the production of 50 circuit arrangements whereby the apparatus is simplified to the greatest possible extent consistent with good operation, and whereby the operations to be performed by an operator in setting up a call are reduced to the 55 smallest practical number. These objects,

together with the foregoing, will be explained fully hereinafter.

Referring now to the accompanying drawings comprising Figs. 1-6, inclusive, they show by means of the usual circuit diagrams 60 a sufficient amount of apparatus in a system embodying the principles of the invention to enable all the new features of the case to be understood. In order for the drawings to be understood best, Fig. 2 should be placed 65 beneath Fig. 1, with Fig. 3 to the right of Fig. 2, and with Fig. 4 to the right of Fig. 3. Figs. 5 and 6 show a desirable modification of the circuit arrangements at the "B" operator's position and, when used, should be 70 substituted for Figs. 1 and 2, respectively.

Fig. 1 shows a trunk line extending from the jack J at an "A" operator's position in a manual office by way of the trunk circuit TC at a "B" operator's position to the selector D in an automatic office. The remaining equipment shown in this drawing and in Figs. 2-4, inclusive, is located at the office in which the "B" operator's position is located. This position may be located either 75 in the calling manual office or in the automatic office, depending upon which is more economical in any given case.

The selector D, Fig. 1, is mechanically of the well known vertical and rotary type of 80 switch having its bank contacts arranged in horizontal rows or levels, and its circuits are arranged for the well known two-wire method of operation.

The finder F, Fig. 1, is mechanically of the 85 well known rotary type of switch whose wipers are advanced in a forward direction only and have no normal position. This finder has access to a group of trunks of which the trunk circuit TC is one.

The register-sender selector, Fig. 2 is 90 mechanically the same type of switch as the finder F and has access to a plurality of register senders, one of which is shown in Figs. 3 and 4. The finder F and the register-sender selector RSS, together with the associated relays, are termed a finder-selector link and will be referred to hereinafter as a link circuit. It has been assumed that there are three of these link circuits at the 105 "B" position shown, although this number may be increased to any desired number in case it is found that three of them are not enough.

The link selector LS, Fig. 2, is mechanical- 110

ly identical with the register-sender selector RSS and the finder F, and it connects the operator's numerical push buttons with an idle one of the three link circuits.

- 5 It may be pointed out that, in case the trunks at the "B" operator's position are greater in number than the sets of contacts in the bank of the finder F, a twin finder 70 may be connected to the link circuit through 10 the medium of conductors 91-95, inclusive, as is indicated in the drawing. In this case, the finder F has access to part of the trunks and the twin finder has access to the remaining part of the trunks, separate start 15 wires being used for each group.

The register set shown in Fig. 3 comprises the four digit registers DR-1-DR-4, inclusive. Each of these registers is arranged to ground a certain one of the ten impulse 20 stop conductors 251-260, inclusive, under the control of the operator's numerical push buttons. The relays 205, 215, 225, and 235, it may be pointed out, when taken together, 25 constitute a register control sequence switch, and the two step relays 206, 216, 226, and 236, taken together comprise a sender controlling sequence switch. Regarding these 30 two step relays, relay 206 for example, it may be pointed out that the lower winding 35 consists of a small number of turns of high resistance wire, while the upper winding consists of a large number of turns of relatively low resistance wire. The adjustment of this relay is such that when current flows through 40 the lower winding alone the locking contact marked "1" closes, while the remaining contacts of the relay remain as they are. These remaining contacts are marked "2" to indicate that they operate upon the second 45 step of the relay which occurs when it is energized through its two windings in series.

The sender, Fig. 4, is mechanically of the well known rotary type of switch whose wipers move in a forward direction only and 50 are advanced upon the deenergization rather than upon the energization of the stepping magnet.

A more or less general description of the apparatus having been given, the detailed 55 description of the operation will now be taken up. For this purpose it will be assumed that the "A" operator receives a call for a subscriber whose line terminates in the automatic office to which calls are handled 60 through the "B" position shown in Fig. 1. Accordingly, the "A" operator communicates with the "B" operator through the medium of the well known order wire (not shown) and informs the "B" operator of the desired number, together with the identity 65 of the calling office. The "B" operator accordingly assigns a trunk to the "A" operator in the group belonging to the calling office, the trunk comprising conductors 2 and 3, for example, associated with the jack

J at the calling "A" position. The "B" operator also depresses her non-locking assign button 22, thereby placing ground on the start wire 31 at the lower contacts of the said push button. Also, the normal 70 ground potential is removed from test conductor 30 at the upper main spring of the push button and the conductor 30 is connected with relay 21. The operator is instructed to hold the push button 22 depressed until 75 the indicating lamp 101, associated with her key set, Fig. 2, becomes lighted in a manner which will now be explained.

Responsive to the ground potential being placed upon start conductor 31, relay 98 80 energizes through its left hand winding and places ground on conductor 83 at armature 99 so as to prevent the energization of relay 131 of the link circuit shown in Fig. 2 while the start wire is still grounded. As a further result of the placing of the ground potential on start conductor 31, a circuit is closed for relay 66 through the normally closed contacts controlled by armature 73, which circuit includes also conductor 81, armature 83 99 and its working contact, and resistance 129. Start relay 66, upon energizing, places ground on conductor 85 at armature 76, thereby starting the operation of the register sender selector RSS of the pre-selected 100 link circuit #1 in a manner to be pointed out more fully hereinafter. Relay 66 also closes at armature 78 a circuit for switching relay 65 and stepping magnet 67 in series, and at armature 77 connects test wiper 68 105 to the junction of relay 65 and stepping magnet 77. Assuming first that the wipers 68-70, inclusive, of the finder F are standing upon the contacts in which conductors 28-30, inclusive, of the trunk circuit TC terminate, the operation of armature 77 does not perform any particular function owing to the fact that conductor 30 is ungrounded, and switching relay 65 energizes immediately, seizing the trunk circuit TC. Assuming, however, that the wipers 68-70, inclusive, are standing upon some other set of contacts as indicated in the drawings, test wiper 68 is in engagement with a grounded contact and switching relay 65 is short circuited and does not energize. In this case, stepping magnet 67 is energized through test wiper 68, and the wipers of the finder are advanced step by step in search of the 110 trunk circuit TC owing to the buzzer-like 115 action of stepping magnet 67, which interrupts its own circuit.

When the contacts in which the conductors 28-30, inclusive, terminate are reached, test wiper 68 engages an ungrounded test contact and switching relay 65, being no longer short circuited, energizes in series with stepping magnet 67. Stepping magnet 67, however, 120 does not energize at this time on account of the high resistance of switching relay 65. 125

Upon energizing, switching relay 65 closes a bridge across wipers 69 and 70 at armatures 74 and 75, which bridge includes conductors 79 and 80 and the normally closed contacts controlled by armature 149, Fig. 2; closes a point in the circuit of the indicating lamp 101, Fig. 2, at armature 71; closes a local circuit for start relay 66 and disconnects it from the start wire at armature 73; and at armature 72 opens the test circuit and places ground on test wiper 68, thereby closing a circuit over conductor 30 and the upper contacts of the assign button for relay 21. Relay 21 accordingly energizes; disconnects ground from the central contact of the assign button at armature 25; and closes a circuit for the busy lamp 8 and the lower winding of the electro-polarized relay 9 in multiple at armature 26, whereupon the lamp 8 becomes lighted to give a subsequent indication to the operator to aid her in assigning non-busy trunks. Relay 9, however, does not operate at this time owing to the fact that its lower winding, consisting of a relatively small number of turns of wire having a comparatively high resistance, is not able to energize the relay sufficiently to attract its armature. As a further result of the energization of relay 21 it connects the closed bridge including conductors 28 and 29 across the conductors leading to the selector D and disconnects the latter from the trunk circuit TC. When this occurs, line relay 35 in the selector D energizes over the above traced closed bridge and closes at armature 40 a circuit for relay 36, whereupon relay 36 energizes and at armature 41 prepares certain operating circuits within the selector, and at armature 42 opens a point in the circuit of release magnet 53 and prepares a circuit for vertical magnet 55.

Returning now to the operation of the link circuit, it will be remembered that, upon the energization of start relay 66, a circuit was closed for start relay 132 of the register sender selector RSS. This circuit includes conductor 85 and armature 107 and its resting contact. Upon energizing over this circuit, start relay 132 closes at armature 156 a circuit for relay 131 as follows: from ground by way of the working contact of armature 154 and said armature, working contact and armature 156, relay 131, resistance 134, armature 153 and its working contact, and resistance 129 to battery. Relay 131, however, does not energize over this circuit, owing to the fact that it is short circuited by the ground potential applied over conductor 83 and through armature 155 and its resting contact to the junction of its winding and resistance 134 by armature 99 of relay 98. As a further result of the energization of start relay 132, it closes at armature 157 a circuit for relay 133 and stepping magnet 135 in series, and at armature 158 connects

test wiper 145 to the junction of the winding of relay 133 and the winding of stepping magnet 135. Accordingly, the register-sender selector RSS selects an idle register sender in substantially the same manner as the trunk circuit TC was selected by the finder F, and when an idle register sender is reached by the wipers 141-146, inclusive, under the control of stepping magnet 135, switching relay 133 is no longer short circuited and energizes in series with stepping magnet 135, which magnet does not energize at this time on account of the relatively high resistance of switching relay 133. Upon energizing, switching relay 133 disconnects test wiper 145 from the junction of relay 133 and stepping magnet 135 and connects it to ground instead, thereby making the seized register sender busy to the other selectors having access to it; connects up the wipers 141-144, inclusive, and 146 at armatures 161-164, inclusive, and 166, respectively; and at armature 159 completes a circuit for the lamp 101 as follows: from ground by way of the working contacts and armature 71, conductor 84, working contact and armature 159, contact in the bank of wiper 125 and said wiper, and the lamp 101 to battery. Responsive to the closure of this circuit, the lamp 101 becomes lighted, informing the operator that she may now release the assign push button and set up the desired number on her number push buttons. When the assign button is released, ground is removed from start wire 31, permitting relay 98 to deenergize, whereupon ground is removed from conductor 83, permitting relay 131 to energize over its above traced circuit, which includes armature 156 and its working contact and resistance 134. Relay 131, upon energizing, disconnects conductor 83 from the junction of its own winding and resistance 134 and connects it to conductor 110 for a purpose to be explained hereinafter.

The operator may now proceed to set up the number which we will assume is the number 5678. Accordingly, the operator first depresses the fifth push button, thereby grounding wipers 122 and 124, causing a ground potential to be extended through the working contacts and armatures 162 and 164, wipers 142 and 144, conductors 172 and 174, and the second and fourth armatures of relay 205 and their respective resting contacts to relays 202 and 204. Accordingly, relays 202 and 204 become energized and each closes a locking circuit for itself at its left hand armature through relay 205 and the grounded test conductor 175. The locking circuit for these relays does not become effective immediately, however, owing to the ground extended to each over the above traced circuits. However, when the operator releases the fifth push button, the initial

circuits of relays 202 and 204 are opened, whereupon the locking circuit for these relays becomes effective and relay 205 energizes; prepares a circuit for the similar relay 215 of the digit register DR-2 at its upper armature, and at its four lower armatures disconnects conductors 171-174, inclusive, from relays 201-204, inclusive, of the digit register DR-1 and extends them to relays 211-214, inclusive, respectively, of the digit register DR-2.

When the sixth push button is operated for the second digit 6 in the desired number, ground is placed upon wipers 123 and 124, resulting in circuits being closed through the working contacts and armatures 163 and 164, wipers 143 and 144, conductors 173 and 174, third and fourth armatures and their working contacts of the transfer relay 205, and the third and fourth armatures and their resting contacts of relay 215, for relays 213 and 214 of the second digit register DR-2. Accordingly, relays 213 and 214 energize and each closes at its left hand armature a locking circuit for itself through transfer relay 215 and the upper armature and its working contact of the transfer relay 205. This locking circuit, however, does not become effective until the operator releases the push button, at which time the short circuit is removed from around relay 215, permitting it to energize and transfer the conductors 171-174, inclusive, to the relays 221-224, inclusive, respectively, of the third digit register DR-3.

When the operator depresses the seventh push button, ground is placed on wiper 121, thereby closing a circuit through the resting contact and armature 150, working contact 40 and armature 161, wiper 141, conductor 171, first armature and working contact of relay 205, first armature and its working contact of relay 215, and the first armature and its resting contact of relay 225 for relay 221. 45 Relay 221 accordingly energizes and completes a locking circuit for itself at its left hand armature, which becomes effective upon the release of the seventh push button to maintain the relay locked up and to energize the transfer relay 225, which transfers the conductors 171-174, inclusive, to the relays 231-234, inclusive, of the fourth digit register DR-4.

When the operator depresses the eighth 55 push button for the fourth and last digit in the desired number, ground is placed on the second wiper 122 of the link selector, closing a circuit as previously traced to conductor 172 and thence by way of the second armatures and working contacts of relays 205, 215, and 225 for the second relay 232 of the fourth digit register DR-4. Relay 232 accordingly energizes and at its left hand armature closes a locking circuit for itself 60 which, upon the release of the eighth push

button by the operator, is effective in holding the relay locked up and in energizing relay 235. Relay 235, upon energizing, disconnects at its two lower armatures conductors 171 and 172 from relays 231 and 232 and 70 connects them to the impulse conductors 241 and 242. As a further result of the energization of relay 235, it places ground on conductor 270 at its upper armature, thereby grounding start conductor 243 through the 75 lower armature and its resting contact of relay 236, resulting in the sender being started in a manner to be pointed out hereinafter. As a further result of the ground potential being placed on conductor 270, a 80 circuit is closed through the upper armature and its resting contact of relay 236, conductor 176, wiper 146 of the register-sender-selector RSS, armature 166 and its working contact, and relay 128. Relay 128 accordingly energizes; disconnects wipers 141 and 142 from the key set at armatures 149 and 150 and connects them with the conductors 79 and 80, at the same time opening the local bridge across conductors 79 and 80 at the 85 normally closed contacts controlled by armature 149, leaving the line relay of the first selector D energized through conductors 171 and 172 which are now connected through the lower armature and working contacts of the 90 transfer relays 205, 215, 225, and 235 to the closed bridge in the sender including conductors 241 and 242. As a further result of the energization of relay 128, it closes at armature 148 a locking circuit for relay 95 100 including conductor 81' and armature 78' and its working contact, and at armature 147 disconnects the test conductor from relay 130 and connects it to ground. Relay 130 accordingly deenergizes and opens the circuit 105 of relay 131 at armatures 153 and 154, whereupon relay 131 deenergizes. Relay 130 also opens a point in the initial circuit of start relay 66 of the finder F, leaving the said start relay energized over the locking conductor 81'.

Responsive to ground being placed on the test conductor of the link at armature 147 of relay 128, as above pointed out, a circuit is closed through test wiper 126 and interrupter contacts 105 for stepping magnet 102 of the link selector, whereupon the said stepping magnet energizes and interrupts its own circuit, resulting in the wipers 121-126, inclusive, being advanced into engagement with 115 the contacts of the first idle sender.

Returning now to the sender, Fig. 4, responsive to the ground being placed upon start conductor 243 upon the operation of the transfer relay 235 of the units register, above pointed out, a circuit is closed through the interrupter 304, (upon the first succeeding operation of the interrupter), resting contact and armature 310, and stepping magnet 303 to battery. Stepping magnet 303 120 125 130

accordingly energizes and moves the associated pawl into engagement with the next notch in the wiper driving ratchet wheel. Magnet 303 also opens at contacts 301 a point 5 in the bridge across conductors 241 and 242, but nothing happens responsive to this owing to the fact that contacts 301 are shunted by armature 312 and its resting contact. Upon the subsequent deenergization of stepping 10 magnet 303, due to the operation of the interrupter 304, the wipers 307 and 308 are advanced one step, whereupon wiper 307 engages a grounded bank contact, closing a circuit for pick-up relay 306. Relay 306 accordingly energizes and places ground on conductor 244 at armature 313 through armature 311 and its resting contact. Responsive 15 to the ground potential being placed upon the conductor 244, the lower winding 20 of the two step relay 206, Fig. 3, is energized through the upper armature and resting contact of the said relay 206, whereupon the armature proper of the relay takes the first step, closing the locking contacts indicated 25 by the number 1 on the drawings. This winding, however, does not energize the relay sufficiently to cause the remaining contacts to be operated at this time.

As a further result of the above mentioned 30 operation of pick-up relay 306 of the sender, it removes the shunt from around the interrupter contacts 301 at armature 312. Accordingly, upon each of the following energizations of stepping magnet 303, the bridge across conductors 241 and 242 is opened at contacts 301, resulting in the deenergization of the line relay 35 of the selector D, Fig. 1. The operations of the stepping magnet 303 continue under the control 35 of interrupter 304 until five interruptions have been produced in the outgoing control circuit at contacts 301 or, in other words, until the digit 5 has been sent out. Following the fifth interruption in the outgoing control circuit, stepping magnet 303 deenergizes and advances wiper 308 into engagement with the fifth impulse stop conductor 255, whereupon stop relay 305 is energized over the following circuit: from ground 40 by way of the lower armature of relay 206, Fig. 3, and its resting contact, right hand armature and resting contact of relay 201, right hand armature and working contact of relay 202, middle right hand armature and resting contact of relay 203, middle armature and working contact of relay 204, the fifth impulse stop conductor 255, the associated contact in the bank of wiper 308 and the said wiper, and stop relay 45 305 to battery. Upon energizing, stop relay 305 removes ground from conductor 244 and closes a locking circuit at armature 311, which locking circuit includes armature 313 and its working contact. Responsive to the 50 removal of the ground potential from con- ductor 244, the shunt is removed from around the upper winding of the two step relay 206, whereupon the said relay energizes fully and operates its remaining armatures. At its lower armature, relay 206 disconnects ground from the contacts of the 55 relays 201-204, inclusive, and extends ground through the lower armature of relay 216 and its resting contact to the armatures of the relays 211-214, inclusive. At its upper 60 armature, relay 206 disconnects conductor 244 from the junction of its own windings and extends the said conductor 244 by way of the upper armature of relay 216 and its resting contact to the junction of the wind- 65 ings of the said relay 216.

The thousands digit 5 in the number has been transmitted and the sender is now in an off normal position. Accordingly, it will be necessary to restore the sender to normal before the next digit can be sent out and, for this reason, stop relay 305, upon energizing as above pointed out, in addition to removing ground from the conductor 244 and closing a locking circuit for itself at 70 armature 311, disconnects stepping magnet 303 from the interrupter 304 and connects it to wiper 307 through its interrupter contacts 302. Relay 305 also places a shunt around the sending contacts 301 at armature 309, so as to prevent the outgoing control circuit from being interrupted during the return to normal of the sender. Stepping magnet 303 of the sender now operates in a buzzer-like manner to advance the wipers 307 and 308 to normal. This operation is arrested when wiper 307 passes off the last grounded bank contact. As a further result of wiper 307 passing off the last grounded bank contact, the circuit of pick-up relay 306 is 75 opened. Pick-up relay 306, however, is slow acting and does not deenergize immediately.

In the selector D, Fig. 1, each time line relay 35 deenergizes in response to one of the five interruptions produced in its circuit by the sender as above described, it closes at armature 40 a circuit for vertical magnet 55 as follows: from ground by way of the resting contact and armature 48, armature 40 and its resting contact, armature 42 and its working contact, series relay 37, and vertical magnet 55 to battery. By the operation of vertical magnet 55, the wipers 50-52, inclusive, of the switch are raised step by step and come to rest opposite the fifth level of bank contacts. Relay 37 is energized in series with vertical magnet 55 and, being slow acting, maintains its armature attracted throughout the vertical movement. Relay 37, in combination with off normal contacts 56, which close upon the first vertical step, closes at armature 43 a circuit through interrupter contacts 57 for stepping relay 38. Stepping relay 38 thereupon energizes and closes a locking circuit for 80 100 105 110 115 120 125 130

itself at armature 44, and at armature 45 prepares a circuit for rotary magnet 48.

At the end of the vertical movement, slow acting series relay 37 deenergizes and completes the circuit of rotary magnet 58, whereupon rotary magnet 58 energizes and advances the wipers into engagement with the first set of bank contacts in the selected level, and, near the end of its stroke, opens the circuit of stepping relay 38 at interrupter contacts 57. Stepping relay 38 accordingly deenergizes and opens the circuit of rotary magnet 58 at armature 45, whereupon rotary magnet 58 deenergizes also and again closes its interrupter contacts 57.

Assuming that the trunk terminating in the first set of bank contacts is idle, no ground potential is encountered by test wiper 51 and switching relay 39 energizes immediately, seizing the trunk. In this case, however, it will be assumed that the trunk terminating in the first set of bank contacts is busy, in which case test wiper 51 engages a grounded bank contact and switching relay 39 is short circuited and does not energize. Stepping relay 38, however, energizes from the ground potential encountered on the busy test contact by test wiper 51, and again closes a circuit for rotary magnet 58, whereupon rotary magnet 58 energizes again and advances the wipers into engagement with the next set of bank contacts. The above alternate operation of stepping relay 38 and rotary magnet 58 continues until an idle trunk is reached, which trunk, it will be assumed, is the one comprising conductors 59-61, inclusive, and extending to a hundreds selector (not shown). When this idle trunk is reached, switching relay 39, being no longer short circuited, energizes in series with stepping relay 38. Stepping relay 38, however, does not energize owing to the high resistance of switching relay 39. Switching relay 39, upon energizing, opens the test circuit and prepares the holding circuit at armature 47, thereby extending ground ahead on test wiper 51 and the selected test contact to the release trunk conductor 60, making the seized trunk busy to the other selectors having access to it; disconnects ground from armature 40 of line relay 35 at armature 48, thereby opening the circuit of the slow acting release relay 36; and at armatures 46 and 49 disconnects the incoming trunk conductors from the windings of line relay 35 and extends them by way of wipers 50 and 52 to the corresponding conductors of the seized trunk. Responsive to the seizure of this trunk, holding ground is placed on release trunk conductor 60 in the usual manner, resulting in a holding circuit for relay 39 being closed through test wiper 51 and armature 47 and its working contact before the slow acting release relay 36 has had time to deenergize.

Returning now to the sender, Fig. 4, slow acting pick-up relay 306 deenergizes after an interval and opens the locking circuit of stop relay 305 at armature 313. Stop relay 305 is also slow acting and maintains its armature 70 attracted for an interval, after which it deenergizes and disconnects stepping magnet 303 from wiper 307 and again connects it with the interrupter 304. It may be pointed out that the interval required for relays 306 75 and 305 to fall back one after the other is made long enough to permit the change-over and trunk-hunting operations of the selector D above described to take place before the next digit is transmitted. 80

The hundreds digit 6 in the desired number is now transmitted in the same manner as was the thousands digit 5 and is terminated at the end of the sixth interruption in the outgoing control circuit upon the energization of stop 85 relay 305 over the following circuit: from ground by way of the lower armature and working contact of relay 206, lower armature and resting contact of relay 216, right hand armature and resting contact of relay 211, right hand armature and resting contact of relay 212, right hand armature and working contact of relay 213, second armature (counting from the right) of relay 214 and its working contact, the sixth impulse stop conductor 256, and thence to battery by way of wiper 308 and stop relay 305. The energization of stop relay 305 results in the wipers of the sender being again advanced to normal position and results also in the ground potential being removed from conductor 244, whereupon the two-step relay 216 is energized by its two windings in series (the lower winding of relay 216 having energized and operated the first step locking contacts at the beginning of the second digit) and operates its upper and lower armatures, transferring the circuits controlled thereby to the tens register. 95

Responsive to the transmission of the 110 second digit 6, the selected hundreds selector is operated in the same manner as described for the thousands selector D and selects an idle connector switch in the usual manner. 115

The sender is again started and this time sends out the tens digit 7 in the number, which digit is terminated in the usual manner upon the energization of stop relay 305 over the following circuit: from ground by way of the lower armature and working contact of relay 206, lower armature and working contact of relay 216, lower armature and resting contact of relay 226, right hand armature and working contact of relay 221, middle armature and resting contact of relay 222, inner right hand armature and resting contact of relay 223, inner right hand armature and resting contact of relay 224, the seventh impulse stop conductor 257, the 125 130

associated contact in the sender bank, wiper 308, and relay 305 to battery.

Responsive to the transmission of this digit, the selected connector is operated to raise its wipers opposite the seventh level of bank contacts.

The sender is again started and this time sends out the fourth and last digit, the units digit 8, in the desired number. This digit is terminated by the energization of stop relay 305 over the following circuit: from ground by way of the lower armature and working contact of relay 206, lower armature and working contact of relay 216, lower armature and working contact of relay 226, right hand armature and resting contact of relay 231, right hand armature and working contact of relay 232, middle right hand armature and resting contact of relay 233, third armature (counting from the right) and its resting contact of relay 234, the eighth impulse stop conductor 258, the corresponding contact in the sender bank, wiper 308, and stop relay 305 to battery.

Responsive to the above transmission of the units digit 8, the connector in use is operated to connect with the desired line and thereupon signals the called subscriber in the usual manner.

Responsive to this energization of stop relay 305, ground is again removed from conductor 244 at armature 311, in addition to the usual closure of the restoring circuits at armatures 309 and 310. Responsive to this removal of ground from conductor 244, the two-step relay 236, which also energized part way at the beginning of the last digit, energizes through both its windings in series; disconnects ground from the interrupter 304 at its lower armature so as to prevent the sender from again starting after it is restored; and at its upper armature removes ground from conductor 176, opening the circuit of relay 128 in the link circuit, Fig. 2. Relay 128 accordingly deenergizes and replaces the local bridge across conductors 79 and 80 at the normally closed contacts controlled by armature 149, and at armatures 149 and 150 disconnects the wipers 141 and 142 from conductors 79 and 80. Relay 128 also opens the locking circuit of start relay 66 of the finder F at armature 148, and at armature 147 removes ground from the test conductor of the link and connects the said test conductor to relay 130 again. The finder is now rendered selectable to the link selector LS.

Responsive to the opening of its locking circuit, relay 66 of the finder F deenergizes and opens the circuit of relay 21 of the trunk circuit TC at armature 77, whereupon relay 21 deenergizes and replaces ground on the test conductor 30 at armature 26, and at armatures 23 and 27 disconnects the trunk

conductor extending to the selector D from conductors 28 and 29 and connects them to the trunk circuit TC again.

In the finder F, as a further result of the deenergization of relay 66, it opens the circuit of relay 65 at armature 78, whereupon relay 65 deenergizes, disconnecting the wipers 69 and 70 at armatures 74 and 75, and at armature 71 removes ground from conductor 84, whereupon relay 132 of the switch RSS deenergizes and at armature 157 opens the circuit of the slow acting relay 133 and closes a circuit through armature 158' and its working contact for stepping magnet 135. Relay 133, being slow acting, maintains its armature attracted for an interval and accordingly the circuit of stepping magnet 135 remains closed long enough to energize the magnet. The wipers, however, are not advanced upon the energization of the magnet, the mechanical construction of the register-sender selector being similar to that of the sender. When relay 133 deenergizes, it disconnects the wipers 141-146, inclusive, at armatures 161-166, inclusive, thereby freeing the sender. Also relay 133 opens the circuit of stepping magnet 135 at armature 158', whereupon magnet 135 deenergizes and advances the associated wipers into engagement with the next set of bank contacts. This step is taken by the wipers in order to insure that the same sender is not repeatedly employed to send out successive numbers. If this were not done, the register-sender selector might become set on a defective sender, thereby completely tying up the service from that link circuit. With the present arrangements, however, a new sender is taken into use by the link circuit each time it is used.

In the register sender, responsive to the removal of ground from test conductor 175 by the link circuit, relays 205, 201, and 204 deenergize, and relay 205 opens the circuit of relays 206 and 215, whereupon these relays, as well as the relays 213 and 214, deenergize also. In the same manner the remaining energized relays in the register set are deenergized.

Returning now to the established connection, it may be seen that with relay 21 deenergized, the holding of the connection is dependent upon the energization of relay 7, which in turn is dependent upon the plugging in of the "A" operator. In case the "A" operator has not plugged in, the bridge across the trunk conductors is open at armature 12 of relay 7 and the established connection is released. Assuming, however, that the "A" operator plugged in prior to the deenergization of relay 21, which she has ample time to do after the trunk is assigned to her and before a number set up by the "B" operator is sent out, relay 7 energizes responsive to the plug of the "A" operator.

ator's cord circuit being inserted into the jack J and closes a bridge across the associated trunk conductors at armature 12, which bridge includes the impedance 10 and the upper winding of the electro-polarized relay 9. Relay 7 also closes a multiple circuit for the lamp 8 and the lower winding of the electro-polarized relay 9. Accordingly, when the deenergization of relay 21 takes place, the busy lamp 8 remains lighted through armature 13 and its working contact after its initial circuit is opened at armature 26 and the connection is held up through the bridge which is closed at armature 12 of relay 7. The electro-polarized relay 9, however, is not operated at this time owing to the fact that the current flow in either winding opposes the current flow in the other winding.

When the called subscriber responds to the ringing of his bell, which is accomplished by ringing current sent out through the connector switch in the usual manner, the back bridge relay of the connector switch in use reverses the direction of current flow in the calling loop, whereupon the electro-polarized relay 9 responds owing to the fact that the current flow in its upper winding now assists the current flow in its lower winding in energizing the relay. Upon operating, relay 9 places a shunt around the high resistance 11 so as to extinguish the calling supervisory lamp in the calling operator's cord circuit.

When the called subscriber replaces his receiver, the back bridge relay in the connector switch in use reverses the current flow in the calling loop back to normal, whereupon the electro-polarized relay 9 responds by retracting its armature 14, reinserting the resistance 11 in series with relay 7 so as to again light the calling supervisory lamp in the "A" operator's cord circuit.

When the "A" operator pulls down the connection at her position, relay 7 in the trunk circuit TC deenergizes and opens the circuit of the busy lamp 8 and the lower winding of the electro-polarized relay 9 at armature 13, and at armature 12 opens the bridge across the associated conductors leading to the selector D. Responsive to this, the connection is released in the usual manner, the selector D being released responsive to the deenergization of switching relay 39 which occurs when ground is removed from the release trunk conductor 60. The direct release of the selector D, it may be pointed out, is brought about in the usual manner by the energization of release magnet 53 through the resting contact and armature 48, armature 40 and its resting contact, armature 42 and its resting contact, and off normal contacts 54. The circuit of release magnet 53 is again opened at off normal con-

tacts 54 when the switch is restored to normal position.

In order to explain certain features provided to take care of irregularities, it will be assumed that the operator sets up a number on her key set, but that she does not fully depress one of the keys, in which case the first three digit registers DR-1-DR-3, inclusive, are operated but the fourth digit register DR-4 is not operated. Accordingly, relay 235 is not energized and conductor 176 is accordingly not grounded. Accordingly, relay 128 does not energize to step the link selector LS off the link circuit #1 and the lamp 101 remains lighted, informing the operator that the complete number is not set up. In this case, the operator is not sure whether she failed to depress one of the keys sufficiently or whether the register set in use failed to operate in the correct manner. At any rate, the operator depresses the sender release push button, closing a circuit for relay 106. Relay 106, upon energizing, opens the circuit of relay 132 of the link circuit at armature 107. Relay 132 accordingly deenergizes opening the circuit of relay 133 and closing a circuit for stepping magnet 135. Relay 133 accordingly deenergizes and frees the register sender, and stepping magnet 135 then deenergizes and advances the associated wipers into engagement with the next set of bank contacts.

It will be noted that relay 106 disconnects the start relays of all three link circuits when the sender release button is operated. However, considering the link circuit #1, start relay 132 does not deenergize responsive to the energization of relay 106 in case the sender release button is operated subsequent to the energization of relay 128, because the latter closes a multiple circuit for start relay 132 at armature 191.

When the operator releases the sender release push button, relay 106 deenergizes and again closes the circuit of relay 132 at armature 107, whereupon the register-sender selector RSS is operated to select a new sender, the one last used now being last choice owing to the fact that the wipers of the register-sender selector RSS start on the contacts just ahead of the sender last used. The operator now sets up the desired number in the usual manner.

It will now be assumed that the "B" operator has assigned the trunk circuit TC and that the link circuit #1 is in use in connection with the register sender shown in Figs. 3 and 4, but that the operator cannot remember the correct number. In this case, the operator, of course, could set up a predetermined number that would trunk the call to a monitoring operator's position. In case, however, that it is not desirable or expedient to do this, the operator may free

her push buttons by depressing the link release button, thereby placing ground on conductor 110. This closes a circuit for the slow to energize relay 103. The fact that relay 103 is slow to energize is indicated by a solid black portion of the core instead of the usual shaded portion, such as the one on the lower end of relay 133. A relay like 133 is not especially slow to pull up owing to the fact that the copper slug is placed on the heel end thereof, while relay 103 is both slow to pull up and slow to fall back, because the copper slug is placed on the armature end of the relay, thereby intercepting the lines of force on their way to the armature. The placing of ground on conductor 110 results in the closing of a circuit for stepping magnet 102 in multiple with relay 103 and through armature 104 and its resting contact. Magnet 102 accordingly energizes and moves the associated pawl (not shown) into engagement with another notch in the wiper driving ratchet wheel but does not move the switch wipers.

Responsive to the above operations, relay 130, which was formerly energized through stepping magnet 102, deenergizes and opens the circuit of start relay 66 at armature 151, and the circuit of relay 131 at armature 154, whereupon the link circuit is released in the hereinbefore described manner.

After an interval which is sufficiently long to allow the stepping magnet 102 to operate fully, relay 103 energizes and disconnects stepping magnet 102 at armature 104, whereupon stepping magnet 102 deenergizes and advances the wipers 121-126, inclusive into engagement with the next set of bank contacts.

In case the link circuit terminating in this next set of bank contacts is busy, the wipers are advanced still further and the next idle one is seized and the operator is now free to assign a new trunk.

Regarding the call for the number which the operator forgot, the calling subscriber will, in all probability, wait awhile and then signal the "A" operator who will put the call through as a new call.

In case the operator fails to set up a complete number, or in case the register fails to actuate properly to register a complete number, relay 128 fails to operate, as above pointed out; relays 130 and 131 remain energized; and the lamp 101 is not extinguished, informing the operator, as pointed out hereinbefore, that a complete number has not been registered. However, owing to a rush of work, the operator may fail to note that the lamp 101 is not extinguished after she has depressed the last push button, and she may assign a new trunk with the lamp still lighted. In this case, the link selector is still standing on the link circuit used in the previously attempted call and an idle link circuit is not available for the new call. Accordingly, arrangements have been provided for causing the link selector to pre-select a new link circuit in case the start wire is again grounded under the conditions just pointed out. In this case, when the start wire is grounded, relay 98, Fig. 1, energizes over the start wire and places ground on conductor 83, and, since relay 131 is still energized, the ground potential is extended through armature 155 and its working contact to relay 103 by way of conductor 110, and through armature 104 and its resting contact to stepping magnet 102. This results in the stepping magnet of the link selector LS being operated in the previously described manner to select a new link circuit, the link circuit in use being released responsive to the deenergization of relay 130. Since the operator is instructed to hold the assign button depressed until she sees her lamp 101 become lighted, the slightly delayed operations, due to the fact that the old link circuit must be freed and a new one pre-selected, do not cause any harm to result, and the operator releases the assign button when she sees the lamp 101 become lighted when the newly allotted link circuit completes its operations.

Regarding the operation of the twin finder, one of which may be associated with each of the finders such as F, it may be stated that this twin finder operates in the same manner as the other finder, its circuits being identical with the circuits of the finder F. The one difference is that when a trunk is assigned in the group to which the twin finder has access, the start wire of the twin finder instead of the start wire of the finder F is grounded, whereupon the start relay of the twin finder instead of the start relay of the finder F is operated. Relay 98 is of course common to both finders, one winding associated with each.

Referring now particularly to Figs. 5 and 6, the desirable modification shown therein will now be explained. The principal difference between the arrangement shown in Figs. 5 and 6 and the arrangement shown in Figs. 1 and 2 is that the mechanical finders, such as F, have been replaced in Fig. 5 with a relay per trunk for each of the link circuits, and the remaining circuits have been suitably modified, the circuits of the register sender and of the register-sender selector, however, being the same in both cases.

It is thought that the modification will be best understood from a detailed description of its operation. For this purpose, it will be assumed that the "B" operator at whose position the equipment shown in Figs. 5 and 6 is located, receives a call over the order wire and assigns the idle trunk comprising conductors 401 and 402 to the

calling "A" operator. The "B" operator thereupon operates the assign key 413, placing ground on conductors 414, 415, and 416 leading to the lower windings of relays 431, 432, and 433. Relay 431 is individual to the link circuit #1' and relays 432 and 433 are individual to the link circuits #2' and #3', respectively. Since the link selector LS', Fig. 6, is standing on the contacts of the link circuit #1', and not on the contacts of either of the other two circuits, only one of these three relays, relay 431, is able to energize, no battery being available to energize relays 432 and 433. The circuit over which relay 431 is energized is as follows: from ground by way of contacts of the assign key, conductor 414, lower winding of relay 431, conductor 454, resting contact and armature 534, resting contact and spring 511 of the busy key, the test wiper 526 of the switch LS', interrupter contacts 505 and stepping magnet 502 to battery. Stepping magnet 502 does not energize over this circuit on account of the high resistance of the lower winding of relay 431. Relay 431, upon energizing, locks itself to ground at armature 438 independent of conductor 414; connects the closed bridge including conductors 452 and 453 across the conductors 444 and 445 leading to the associated selector switch and disconnects the said conductors from the open bridge in the trunk circuits TC' at armatures 434 and 439; closes a circuit for the lower winding of the electro-polarized relay 404 and the busy lamp 408 at armature 435; prepares a locking circuit for its upper winding at armature 437; and at armature 436 closes a starting circuit for the register-sender selector RSS' as follows: from ground by way of the resting contact and left hand armature of relay 440, working contact and armature 436; conductor 456, start relay 528, and the resistance 530 to battery. Relay 528, however, does not energize as long as the assign key is depressed, owing to the ground potential applied over the common conductor 457 and through armature 537 and its resting contact to the junction of the winding of relay 528 and the resistance 530.

When the operator releases the assign key, the lower winding of relay 431 remains locked up at armature 438, and ground is removed from conductor 457, permitting start relay 528, Fig. 6, to energize over its circuit traced above. Upon energizing, relay 528 disconnects conductor 457 from the junction of its own winding and the resistance 530 at armature 537 and extends the said conductor through armature 537 and its working contact, and through the resting contact and armature 531 to the common link release conductor 510 so as to cause a new link to be allotted in case the

operator depresses another assign key before the call over the trunk circuit TC has been set up. Relay 528 also closes a circuit for relay 529 and stepping magnet 548 in series at armature 538, and at armature 539 connects test wiper 555 to the junction of relay 529 and magnet 548. Accordingly, the register-sender selector RSS' selects an idle register sender in the hereinbefore described manner, whereupon relay 529 energizes and seizes the selected register sender, and at armature 547 closes a circuit for the lamp 501 to inform the operator that she may set up the number.

The operator now sets up the desired number in the usual manner, and, when the number is completely set up, conductor 176 is grounded by the register in the usual manner, closing a circuit through wiper 556 and armature 546 and its working contact for relay 527, whereupon relay 527 energizes; closes a local circuit for start relay 528 at armature 533; closes a locking circuit for the upper winding of relay 431 at armature 532 over conductor 455 and through armature 437 and its working contact; disconnects the common conductor 510 from conductor 457 at armature 531; at armature 534 opens the circuit of the lower winding of relay 431, leaving the said relay 431 energized over its upper winding; and at armature 534 and its working contact places ground on the test conductor leading to the bank of the link selector LS'. Accordingly, the link selector LS' is stepped off the link #1' by the action of stepping magnet 502 and pre-selects another idle link circuit.

When the registered number has been completely sent out, ground is removed from conductor 176 by the register in the hereinbefore described manner, whereupon relay 527 deenergizes; opens the circuit of relay 528 at armature 533 and the locking circuit of relay 431 at armature 532. When this occurs, the relay 431 deenergizes and reconnects the two sections of the trunk extending ahead from the trunk circuit TC'.

In the register-sender selector, relay 528 deenergizes responsive to the opening of its circuit and opens the circuit of the slow acting relay 529 at armature 538 and closes a circuit for stepping magnet 548 through armature 540 and its working contact. Accordingly, stepping magnet 548 is energized, and, responsive to the deenergization of relay 529, stepping magnet 548 deenergizes and advances the associated wipers one step.

Regarding the holding up of the established connection, it may be pointed out that the connection is held up in the same manner as was described in connection with Fig. 1, that is, after the "A" operator has plugged in, relay 403 is energized and a circuit is closed at armature 409 for relay 405, which

relay maintains the circuit of the lower winding of relay 404 and of the busy lamp 408 intact at armature 412 after relay 431 has deenergized, and likewise holds the established connection at armature 411 through the bridge including the impedance 407 and the upper winding of the electro-polarized relay 404.

When the called subscriber responds, the 10 electro-polarized relay 404 is operated and it shunts the high resistance winding of relay 403 with the low resistance impedance 406 at armature 410, thereby permitting the calling supervisory lamp in the "A" operator's cord circuit to be extinguished. The 15 impedance 406 is included in the shunt around the high resistance winding of relay 403 in order to make the talking circuit more efficient than it would otherwise be 20 with the lower winding only of relay 403 bridged across the line.

When the called subscriber replaces his receiver, the electro-polarized relay 404 falls back and removes the shunt from around 25 the high resistance winding of relay 403, whereupon the calling supervisory lamp is again lighted and the operator pulls down the connection, resulting in the deenergization of relay 403 followed by the deenergization 30 of relay 405. The busy lamp 408 now becomes extinguished and the connection is released in the usual manner responsive to the opening of the bridge at armature 411.

In case the operator has partially set up 35 a number and wishes to wipe out that number, she presses the sender release button in the upper left hand corner of Fig. 6, closing a circuit over conductor 451 for relay 440, whereupon relay 440 energizes and removes ground from conductor 441, opening the circuit of start relay 528, Fig. 6, whereupon start relay 528 deenergizes followed by the deenergization of the slow acting 45 relay 529. The stepping magnet 548 is momentarily energized in the usual manner and the associated wipers are advanced into engagement with the next set of bank contacts.

50 When the operator releases the sender release button, the circuit of relay 528 is again established and a new sender is selected in the usual manner, whereupon the operator may set up any desired number.

55 In case the operator desires to release the link, if she finds that she is unable to set up a certain number, or to remember the number, or for any other reason, she operates the link release button, causing a momentary impulse 60 of current to be delivered to stepping magnet 502 owing to the slow to pull up action of relay 503. Accordingly, the circuit of the lower winding of relay 431, Fig. 5, is opened and the relay deenergizes and opens the circuit 65 of start relay 528 at armature 436,

whereupon the register-sender selector RSS' is released in the usual manner.

The link circuit is released in the same manner and a new one is pre-selected in case the operator presses a new assign key before 70 the previous number is completely set up or, in other words, before relay 527 has been energized over conductor 176. In this latter case start relay 528 of the link circuit #1' (assuming that this link circuit is the one 75 in use for the previous call) is energized and relay 527 is deenergized. Accordingly, when the common conductor 457 is grounded upon the new assign key being operated, a ground potential is extended to conductor 80 510 through armature 537 and its working contact and the resting contact and armature 531. After the link selector LS' has operated to pre-select a new link circuit, connection is made with the assigned trunk and 85 with an idle register-sender selector in the hereinbefore described manner.

What I claim is:

1. In a telephone system, a plurality of trunk lines, a plurality of sending mechanisms, a set of number keys, a signal individual to said keys, operator controlled automatic means for connecting said key set with an idle sender and for connecting said sender with a calling trunk line, and means responsive only to the completion of both operations for operating said signal. 95

2. In a telephone system, a link circuit comprising a forward hunting switch and a plurality of backward hunting switches, a 100 plurality of starting circuits, one for each of said backward hunting switches, means for closing any one of said starting circuits, and means responsive thereto for starting the corresponding backward hunting switch and 105 for directly starting said forward hunting switch.

3. In a telephone system, a plurality of trunk lines, a plurality of senders, a plurality of link circuits for connecting any sender to 110 any trunk line, a link allotter, means including testing means for automatically maintaining said allotter associated with an idle link circuit, and operator controlled means for advancing said allotter independent of 115 said automatic means.

4. In a telephone system, a plurality of register senders, a plurality of trunk lines, a plurality of link circuits, each having 120 mechanism for connecting any desired line with any idle register sender, a link allotter for allotting only one link circuit for use at one time, an assign key for each line, means responsive to the operation of an assign key for causing the allotted link circuit to connect the line associated with the operated assign key with an idle register sender, means for operating the selected registering mechanism through the link circuit in use to 125 register a desired number, means for subse- 130

quently transmitting the registered number to the assigned trunk through the link circuit in use, means responsive to the complete registration of the number in the register 5 sender for operating said allotter to allot another link circuit, and means responsive to the operation of a second assign key before the number is completely registered for operating said allotter to allot a link circuit for use 10 to connect the newly assigned trunk with an idle sender.

5. In a telephone system, a plurality of trunk lines extending to automatic switches, a plurality of register senders, a group of 15 link circuits for connecting idle senders with trunk lines over which calls are to be extended, an operator's key set, preselecting switching means for maintaining said key set connected with an idle link circuit and 20 for preventing connection with busy link circuits, means responsive when the operator assigns one of said trunks to a call for causing the preselected link circuit to connect an idle register sender to the assigned trunk, 25 circuit arrangements for causing a number set up on said key set to be registered in the connected register sender, and means responsive to the registration of the last digit in the number for causing the connected register 30 sender to transmit the number through the link circuit in use to the connected trunk line.

6. In a telephone system, a plurality of trunk lines extending to automatic switches, 35 a plurality of register senders, a group of link circuits for connecting idle senders with trunk lines over which calls are to be extended, an operator's key set, preselecting switching means for maintaining said key 40 set connected with an idle link circuit and for preventing connection with busy link circuits, means responsive when the operator assigns one of said trunks to a call for causing the preselected link circuit to connect an idle register sender to the assigned trunk, 45 circuit arrangements for causing a number set up on said key set to be registered in the connected register sender, and means responsive to the registration of the last digit 50 in the number for causing the said switching means to preselect another one of said link circuits.

7. In a telephone system, a plurality of trunk lines extending to automatic switches, 55 a plurality of register senders, a group of link circuits for connecting idle senders with trunk lines over which calls are to be extended, an operator's key set, preselecting switching means for maintaining said key 60 set connected with an idle link circuit and for preventing connection with busy link circuits, means responsive when the operator assigns one of said trunks to a call for causing the preselected link circuit to connect an idle register sender to the assigned trunk, 65

circuit arrangements for causing a number set up on said key set to be registered in the connected register sender, and means responsive to the registration of the last digit in the number for causing the connected register 70 sender to transmit the number through the link circuit in use to the connected trunk line and for causing the said switching means to preselect another one of said link circuits. 75

8. In a telephone system, a plurality of trunk lines extending to automatic switches, other switches, a plurality of register senders, a group of link circuits for connecting idle senders with trunk lines over which calls are to be extended, an operator's key set, preselecting switching means for maintaining said key set connected with an idle link circuit, means responsive when the operator assigns one of said trunks to a call for causing the preselected link circuit to connect an idle register sender to the assigned trunk, 80 circuit arrangements for causing a number set up on said key set to be registered in the connected register sender, means responsive to the registration of the last digit in the number for causing the connected register sender to transmit the number through the link circuit in use to the connected trunk line 85 to operate the associated switch and a plurality of said other switches to complete the connection to the called line, means for connecting the calling line to the trunk line prior to the completion of the operation of said switches, means responsive to the transmission of the last digit in the number for disconnecting the connected register sender from the trunk, and means for automatically releasing all the operated switches in case the calling line has not yet been connected to the 90 trunk line when the register sender is disconnected. 95

9. In a telephone system, a plurality of trunk lines extending to automatic switches, a plurality of register senders, a group of link circuits for connecting idle senders with trunk lines over which calls are to be extended, an operator's key set, preselecting switching means for maintaining said key set connected with an idle link circuit, means responsive when the operator assigns one of said trunks to a call for causing the preselected link circuit to connect an idle register sender to the assigned trunk, circuit arrangements for causing a number set up on said key set to be registered in the connected register sender, means for causing the register sender to transmit the registered number through the link circuit in use to the connected trunk line, means for connecting a calling line to the trunk line, and circuit arrangements for starting the transmission of the number responsive to the registration of the last digit independent of whether the calling line has been connected or not. 100 105 110 115 120 125 129

10. In a telephone system, an operator's link circuit comprising a trunk finder and a register-sender selector, operator-controlled means for actuating the trunk finder to connect the link circuit with a trunk line on which a call is waiting, means for automatically actuating the register selector to select and connect up an idle register sender, and operator controlled means for releasing and reoperating the said register-sender selector to select and connect up another register sender while maintaining the said trunk finder operated. 70
11. In a telephone system, an operator's link circuit, a plurality of register senders, a step-by-step hunting switch for connecting said link circuit to an idle register sender, operator-controlled means for disconnecting said link circuit from a selected register sender and for advancing said hunting switch one step, and means for thereupon automatically operating said hunting switch to connect said link circuit with another idle register sender. 80
12. In a telephone system, an operator's link circuit, a plurality of register senders, a hunting switch for connecting said link circuit with an idle register sender, means for releasing said hunting switch to sever said connection, and means automatically operated upon such release for advancing said hunting switch a single step to associate it with another register sender. 85
13. In a telephone system, a plurality of trunk lines, a plurality of register senders, a plurality of link circuits, each having mechanism for connecting any desired line with an idle one of said register senders, a link allotter for allotting said link circuits for use one at a time, an assign key for each trunk line, means responsive to the operation of an assign key for causing the allotted link circuit to connect the associated line with an idle register sender, and means responsive to a reoperation of the last named assign key for causing said allotter to allot another link circuit for use. 100
14. In a telephone system, a plurality of trunk lines, a plurality of register senders, a plurality of link circuits, each having mechanism for connecting any desired line with an idle one of said register senders, a link allotter for allotting said link circuits for use one at a time, an assign key for each trunk line, means responsive to the operation of an assign key for causing the allotted link circuit to connect the associated line with an idle register sender, and means responsive to an operation of any assign key for advancing said allotter to another link circuit whereby a first link circuit is released and the newly-allotted link circuit is operated to connect the trunk line associated with the last-operated assign key to an idle register sender. 115
15. In a telephone system, a plurality of trunk lines, a plurality of register senders, a plurality of link circuits, each having mechanism for connecting any desired line with an idle one of said register senders, a link allotter for allotting said link circuits for use one at a time, an assign key for each trunk line, means responsive to the operation of an assign key for causing the allotted link circuit to connect the associated line with an idle register sender, operator-controlled means for registering a telephone number on the selected register sender, means responsive to a reoperation of the last-named assign key prior to the registering operation for causing said allotter to allot another link circuit for use, and means controlled from the register sender responsive to the registering operation for removing said allotter from under the control of said assign key. 120
16. In a telephone system, a plurality of trunk lines, a plurality of register senders, a plurality of link circuits, each having mechanism for connecting any desired line with an idle one of said register senders, a link allotter for allotting said link circuits for use one at a time, an assign key for each trunk line, means responsive to the operation of an assign key for causing the allotted link circuit to connect the associated line with an idle register sender, means responsive to the reoperation of the last-operated assign key for causing said allotter to allot another link circuit for use, and operator-controlled means for removing said allotter from under the control of said assign key. 125
17. In a telephone system, a plurality of trunk lines, a plurality of register senders, a plurality of link circuits, each having mechanism for connecting any desired line with an idle one of said register senders, a link allotter for allotting said link circuits for use one at a time, an assign key for each trunk line, means responsive to the operation of an assign key for causing the allotted link circuit to connect the associated line with an idle register sender, and means responsive to the operation of said assign key for rendering said allotter responsive to a subsequent operation of the same or another assign key to allot a new link circuit and release the first one. 130
18. In a telephone system, a plurality of trunk lines, a plurality of register senders, a plurality of link circuits, each having mechanism for connecting any desired line with an idle one of said register senders, a link allotter for allotting said link circuits for use one at a time, an assign key for each trunk line, means responsive to the operation of an assign key for causing the allotted link circuit to connect the associated line with an idle register sender, operator-controlled

means for operating the seized register sender to register and retransmit a number, means controlled by the register sender for releasing the link circuit when the number has 5 been retransmitted, and operator-controlled means for bringing about the release of the link circuit independent of the operation of the register sender.

19. In a telephone system, a plurality of 10 operator's link circuits, a link allotter for allotting said circuits for use one at a time, a test wiper and a driving magnet for said allotter, means for operating said driving magnet in a circuit through said test wiper to bring about said allotting action, and operator-controlled means for operating said magnet to advance said allotter in a circuit 15 independent of said test wiper.

20. In a telephone system, a plurality of 20 operator's link circuits, a link allotter for allotting said circuits one at a time, a test wiper and a driving magnet for said allotter, means for operating said driving magnet in a circuit through said test wiper to bring 25 about said allotter action, means in each link circuit for closing said test-wiper circuit to move the allotter to the next link circuit,

and a circuit independent of the said test wiper for operating said magnet.

21. In a telephone system, a plurality of 30 trunk lines, a plurality of register senders, a plurality of link circuits each having mechanism for connecting any desired line with an idle one of said register senders, a link allotter for allotting said link circuits for 35 use one at a time, an assign key for each trunk line, an allotter-advance key individual to said allotter, means responsive to the operation of an assign key for causing the allotted link circuit to connect the associated 40 line with an idle register sender, means responsive to an operation of the same or another assign key for causing said allotter to allot another link circuit for use, means in each of said link circuits for causing said 45 allotter to allot another link circuit for use, and means including said allotter-advance key for causing said allotter to allot another link circuit.

In witness whereof, I hereunto subscribe 50 my name this 15th day of January, A. D., 1924.

MARTIN L. NELSON.
